CLAIM

The design for an holder for pet food container, as shown and described.

DESCRIPTION

FIG. 1 is a top perspective assembled view of an holder for pet food container including a base and an adapter.

FIG. 2 is a top perspective view of the base of the holder for pet food container.

FIG. 3 is a bottom perspective view of the base of the holder for pet food container.

FIG. 4 is a side view of the base of the holder for pet food container.

FIG. 5 is a front view of the base of the holder for pet food container.

FIG. 6 is an additional side view of the base of the holder for pet food container.

FIG. 7 is a rear view of the base of the holder for pet food container.

FIG. 8 is a top plan view of the base of the holder for pet food container.

FIG. 9 is a bottom plan view of the base of the holder for pet food container.

FIG. 10 is an exploded view of the holder for pet food container depicting the insertion of the adapter into the base and the insertion of the food container into the adapter; and, FIG. 11 is an assembled view of the holder for pet food container depicting the adapter inserted into the base and the food container into the adapter.

The broken line showing of holder for pet food container is included for the purpose of illustrating portions of the article and forms no part of the claimed design.
